UNITED STATES PATENT OFFICE.

WILLIAM MITCHELL, OF MILWAUKEE, WISCONSIN, ASSIGNOR TO MITCHELL MANUFACTURING CO., OF MILWAUKEE, WISCONSIN, A CORPORATION OF WISCONSIN.

CARRIER.

1,241,238.

Specification of Letters Patent. Patented Sept. 25, 1917.

Application filed December 8, 1915. Serial No. 65,650.

To all whom it may concern:

Be it known that I, WILLIAM MITCHELL, a citizen of the United States, and resident of Milwaukee, in the county of Milwaukee and State of Wisconsin, have invented new and useful Improvements in Carriers, of which the following is a description, reference being had to the accompanying drawings, which are a part of this specification.

10 The invention relates to carriers.

The invention is designed more particularly to provide an elevated carrier for use in modern sanitary barn construction for transporting material within or in and 15 out of the barn.

The invention is further designed to provide a new and improved form of lock and trip for the tiltable carrier bucket.

20 The invention is further designed to provide a new and improved form of brake for the raising and lowering mechanism.

25 The invention is further designed to provide in combination with a carrier which rides on both a rail and a wire trolley, a guard for preventing disengagement of the carrier wheels from the track when they pass from the rail to the wire.

With these and other objects in view, the invention consists in the several features 30 hereinafter set forth, and more particularly defined by claims at the conclusion hereof.

In the drawings, Figure 1 is a side view of the device embodying the invention, showing the bucket locked in its lowered 35 position.

Fig. 2 is a side view similar to Fig. 1, showing the bucket unlocked in its raised position, parts being broken away;

Fig. 3 is an end view of the device;

40 Fig. 4 is a section taken on the line 4—4 of Fig. 1;

Fig. 5 is a section taken on the line 5—5 of Fig. 1;

Fig. 6 is a section taken on the line 6—6 of Fig. 1;

Fig. 7 is a section taken on the line 7—7 of Fig. 1 when the bracket is in raised position;

Fig. 8 is a section taken on the line 8—8 of Fig. 1;

Fig. 9 is a section taken on the line 9—9 of Fig. 1;

Fig. 10 is a section taken on the line 10—10 of Fig. 1;

Fig. 11 is a section taken on the line 55 11—11 of Fig. 10;

Fig. 12 is a section taken on the line 12—12 of Fig. 10;

Fig. 13 is a section taken on the line 13—13 of Fig. 10.

The device, in general, comprises a track or trolley, trolley-wheels mounted on said track, a main carrier-frame connected to said wheels and suspended below the track, a bucket or receptacle-carrying frame slidably mounted on said main-frame, a bucket or receptacle swingingly mounted on said bucket-frame, means for locking the bucket in upright position in the bucket-frame, means for controlling the operation of said locking means, mechanism for raising and lowering said bucket-frame, a brake for controlling the raising and lowering mechanism, and guard means for preventing the trolley-wheel from jumping the track.

The track comprises a rail portion 14 of I-beam form, the upper flange portion of the beam forming the running surface which portion is preferably used within the barn and a wire or cable section 15 forming a continuation of the rail and extending outside of the barn to the place where it is desired to unload the material carried by the bucket. The end 16 of the wire is disposed within one side of the channel of the 80 rail 14 and is anchored to the rail supporting hangers 17 and a portion of the wire adjacent said end passes under a clip 18 and is secured therein by a set screw 19, the end 14' of the rail gradually sloping down 85 to the wire.

The trolley-wheels 20 are provided with rail engaging flanges 21 adjacent the sides of the rail and a central circumferential wire engaging groove 22, said wheels being journaled on stud shafts 23 mounted on wheel-supporting brackets 24.

The main carrier frame comprises a pair of upright bars 25 secured at their upper ends by bolts 26 to spaced apart coupling members 27, a longitudinally extending shaft 28 journaled in said members and secured therein adjacent endwise movement by collars 29, and upright extensions 30 on said members having recesses 31 therein for 100 receiving the lower knobbed ends 32 of the brackets 24 and co-operating with detachable locking plates 33 to form a swivel con-

nection between the wheel brackets and the frame.

The bucket-carrying frame comprises a U-shaped frame 35 of channel form with the flange portion of the channel on the outer side, the upright channel portions 36 of said frame adapted to slidably engage the bars 25, the lower ends 37 of said upright portion being provided with inwardly extending bearing brackets 38.

10 The carrier bucket 39 is an open top receptacle, preferably made of sheet metal, the ends and sides of which are secured together by angle iron strips 40, the upper edges 15 of the ends and sides being reinforced by angle-iron strips 41, Figs. 1, 2 and 3. Trunnions 42 are mounted on the ends of the bracket below its center of gravity and are journaled in the bearing brackets 38 so that 20 the open-end of the bucket will be normally disposed below the ends of the bucket-carrying frame and in discharging position unless prevented from doing so by the locking means.

25 The means for locking the bucket in upright position comprises a pair of clips 43 which surround and slidably engage the upright bucket-frame portions 36 and which are provided with locking slots 44 for receiving the locking pins 45 carried on the upper central portions of the ends of the bucket, Figs. 1, 2, 3 and 8. Resultantly, when the swinging bucket is moved to its upright position and the locking pins 45 are 30 disposed within the slots 44 any tendency of the bucket to tip will be prevented and it will then be in loading position, as shown 35 in Fig. 1.

The means for controlling the locking 40 means comprises a trip lever 46 pivotally mounted on a bracket 47 on the transverse portion of the U-shaped frame 35 and flexible connections between said lever and clips 43. These connections consist of chains 48 45 and 49 connected at one of their ends to hooks 50 and 50' on said lever and passing through curved guide channels 51 on the bucket-frame and connected at their other ends to hooks 51' and 51'' on the clips and 50 also chains 48' and 49' connected at one of their ends to the chains 48 and 49 respectively and at their other ends to hooks 52 and 52' at the lower end of the lever 46. The hooks 51, 51'' and 52 and 52' are 55 disposed on opposite sides of the pivot of the lever 46 so that when the lever 46 is shifted to either side of its normal upright position the chains 48, 49' and 49 and 48' will coöperate to raise the clips 43 upwardly out 60 of locking engagement with the pins or lugs 45 on the bucket. When the bucket is in raised position, means are provided to engage the shoe 46' on the lever 46 for automatically actuating the trip lever 46 to release the locking means so that the bucket

may tip to discharge its contents and this consists of a cam bracket or stop 52 which is generally on the wire 15 at a place outside the barn where it is desired to dump the bucket, Figs. 1 and 2.

70 In connection with trip devices of this kind where the trip lever 46 is mounted on the bucket-frame directly below and in line with shaft 28, means are provided for permitting the shoe 46' to clear the shaft 28 75 when the bucket is being brought to its elevated position or is being lowered therefrom. This means comprises the bracket 47 which is pivotally mounted at its lower end 54 upon the top of the channel and adjacent one side thereof of the frame 35 so that it may be brought up to upright position adjacent this side or may swing down toward the other side under which condition its movement is limited by a stop 55, 80 Figs. 6 and 7. The bracket 47 is provided with a hook 56 at its upper end and the lever 46 is pivotally secured below the hook and on the same side of the bracket as the stop 55, so that normally the weight of the 85 lever will swing the bracket and lever outwardly as shown in Fig. 6. Under these conditions, when the bucket-carrying frame is being raised to elevated position the shoe 46' will be tipped over far enough to clear 90 the shaft 28, as shown in Fig. 6 and on a further raising of the bucket frame the hook 56 engages the shaft 28, as shown in dotted lines in Fig. 6, and in full lines in Fig. 7, and swings the bracket and lever upwardly 95 into operative position for engagement of the shoe 46' with the stop or strip 53.

100 The mechanism for raising and lowering the bucket-frame comprises the revoluble shaft 28, flexible connections 57 secured at 105 one of their ends 58 to the coupling members 27 and thence passing over pulleys 59, carried by guide brackets 60 on the bucket-frame, upwardly and wound around and secured at their other ends to clips or collars 110 61 on the shaft 28, a pulley 62 mounted on the end of said shaft 28 and an endless chain 63 passing over said pulley for driving engagement therewith. Resultantly, when the operator pulls on one side of the 115 chain 63, the pulley 62 and shaft 28 are turned to wind up the flexible connections 57 upon the shaft 28, and the pulleys 59 being mounted upon said connections rise, carrying the bucket-frame with them which 120 slides upwardly in the frame bars 25 until the frame reaches its elevated position, shown in Fig. 2.

125 The brake for controlling the raising and lowering mechanism comprises brake shoes 64 and 64' connected to arms 65 and 65' by bolts 66. These arms 65 and 65' are provided with centrally disposed slots for receiving the shaft 28 to loosely mount said brake thereon. The brake arm 65 is pro- 130

vided with an operating handle 68 and a cam slot 69 disposed between the shaft 28 and the brake shoe 64. A cam roller 70 carried by a pin 71 mounted on an extension 72 of one coupling member 27 is movably disposed in said slot. The roller 70 always remains in a relatively fixed position and the cam slot 69 is so formed that when the roller 70 is in midposition both brake shoes 64 and 64' are out of engagement with the brake wheel 62 and the shaft 28 is then free to rotate. When the roller is at the lower end of the slot and the handle 68 is down, the brake shoe 64 will be out of and the brake shoe 64' will be in engagement with the pulley and this will occur whenever the operator moves the lever 68 down. When the operator pulls on the chain 63 to rotate the shaft 28 to pull up the bucket frame, the 20 brake shoe 64 will be automatically moved out of engagement and the arms 65 and 65' will be moved to mid-position so that the shaft 28 may be rotated to raise the bucket frame. When the roller moves upwardly in 25 the slot, the distance between the shoe 64 and the shaft is shortened by the movement of the arms 65 and 65' under the action of the cam 69 and roller-carrying arm 72 and the shoe 64 is thus brought into engagement 30 with the pulley 62 and this occurs whenever the operator releases the lever or when he stops pulling on the chain 63 in the direction shown by the arrow in Fig. 4 as the weight of the bucket and frame acts to reverse the direction of rotation of the shaft 28, thus bringing the roller 70 into the upper portion of the slot 69 and consequently automatically applying the brake to the wheel. When the operator moves the lever 68 down, 40 as previously described, the brake shoe 64' will act to retard the descent of the bucket-frame or to stop it, if desired. Thus the shoe 64 forms in effect a clutch which is automatically released to permit the rotation of the shaft 28 when the chain 63 is operated to raise the carrier frame.

While it is necessary to have a guard for the trolley wheels where they are running on the wire or cable 15 it is likewise necessary to provide for moving this guard up out of the way when the carrier is running on the rail sections, especially on the curves and also to move it out of the path of the lower ends of the rail-supporting hangers 50 17. This guard means consists of a guard plate 73 for each trolley wheel disposed adjacent the outside of the wheel and means for raising and lowering said guard plate.

Each guard plate 73 is fastened to arms 74 which extend around the trolley wheel and thence inwardly into a plate forming connected guide flanges 75 which are slidably mounted in guideways 76 in opposite sides of the bracket 24, Figs. 10, 11, 12 and 13. 65 The means for holding the plate 73 and the

frame formed by the arms 74 and flanges 75 so as to keep the guards above the wheel, as shown in Figs. 1, 9 and 10, comprises a latch 77 pivotally disposed within a slot 78 in the bracket 24. A strap 79 is connected 70 to the flanges 75 and its transverse portion 80 is adapted to rest upon the top 81 of the end of the latch 77, as shown in Fig. 9. The latch 77 is normally held in this position by a spring 82 disposed in the bracket 24 and 75 pressing upwardly against the arm 84 of the latch. To permit the guard plate to drop automatically when the carrier starts on the wire, means are provided for releasing the latch 77 from engagement with the 80 portion 80. This means comprises a finger 85 which rides under a cam trip 86 secured to the rail just before the carrier leaves the rail for the wire, which trip moves the upper end of the latch inwardly and out of 85 engagement with the portion 80 of the guard frame and thus permit the guard to slide down in the guides and be disposed below the wheel at one side, as shown in Figs. 1 and 3. On the return trip of the carrier 90 when it passes from the wire to the rail, the lower end of the guard plate rides up on a cam plate 87 thereby lifting the guard frame upwardly and due to the inclined portion 88 on the end of the latch it is moved 95 past the end of the latch comprising the spring 82 after which the latch, under the action of the spring 82, moves into locking engagement with the portion 80 of the guard-frame and the guard is held in elevated position. 100

The operation of the device in brief is as follows:—

The bracket 39 secured in upright leading position by the clip 43 and pins 45 is filled 105 with the material to be carried out of or within the barn, Fig. 1. Then the operator by turning the shaft 28, through the pulley 62 and chain 63, lifts the bucket-frame and bucket to elevated position, the brake automatically locking the shaft 28 against movement. Then the carrier is moved along on the rail and as it leaves the rail for the wire, the guards fall down at the sides of the wheels. When it has traveled the desired 115 distance on the cable 15 the trip lever 46 strikes the cam 53 thereby releasing the clips 43 from locking engagement with the bracket which, due to its connection with the frame tips over and discharges its contents. 120 The carrier is then returned along the wire and just after it strikes the rail the guards on the trolley wheels are moved upwardly. The rails being mounted in the barn above the space behind the stalls, the carrier may 125 be stopped at any point and the operator by moving the handle 68 of the brake downwardly releases the brake and due to the weight of the frame the shaft 28 is rotated to unwind the chains or flexible connections 130

57 until the bucket is again in lowered position.

The invention thus exemplifies a new and improved form of carrier which is well 5 adapted for the purposes described.

The invention is not to be restricted to the details of construction herein set forth, it being my intention to claim the same as broadly as will be permitted by the state of 10 the art.

What I claim as my invention is:—

1. In an elevated carrier, the combination, with a track, trolley wheels mounted thereon, wheel supporting members and a shaft 15 connected to said members and suspended below said track, of a frame suspended below said shaft, means for raising and lowering said frame, a bucket swingingly mounted in said frame and normally movable to 20 discharging position, means for securing said bucket in upright loading position, and means for automatically releasing said locking means to trip said bucket comprising a bracket pivotally mounted for limited movement on said frame, a trip lever pivotally mounted on said bracket and provided with a hook for engaging said shaft, a trip-shoe 25 normally disposed in inclined position, but movable to upright position on the engagement of the hook with said shaft, and a cam plate on said track for engaging said lever.

2. In an elevated carrier, the combination, with a track, trolley-wheels mounted thereon, wheel supporting members, a main carrier frame connected to said members and suspended below said track including a shaft 35 and a wheel and chain for revolving said shaft, a bucket carried by said frame, and

means connected to said shaft for raising and lowering said bucket, of a brake for said 40 shaft comprising brake-members loosely mounted on said shaft and carrying a brake-shoe, one of said brake-members having a cam slot therein, and a fixed member engaging in said slot to automatically move said 45 brake-members to bring the brake-shoe against the wheel when the chain is released by the operator.

3. In an elevated carrier, the combination, with a main carrier frame including a 50 revoluble shaft provided with a wheel, of a carrier suspended below said frame, means connected to the carrier and said shaft for raising and lowering the carrier on the turning of said shaft, means for turning 55 said shaft, and a brake comprising a pair of brake shoes disposed on opposite sides of said wheel and, means for bringing said shoes into alternate frictional engagement with said wheel.

4. In an elevated carrier the combination, with a main carrier frame including a revoluble shaft provided with a wheel, of a carrier suspended below said frame, means connected to the carrier and said shaft 65 for raising and lowering the carrier on the turning of said shaft, and a brake comprising a clutch shoe for automatically frictionally engaging said wheel on the release of said turning means on the raising of the 70 carrier and a brake shoe for retarding said wheel when the clutch shoe is out on the lowering of the carrier.

In testimony whereof, I affix my signature.

WILLIAM MITCHELL.
